USPC D26/24, 37-52, 60-66
CPC F21Y 2115/10; F21L 4/00
See application file for complete search history.

(56) **References Cited**

The ornamental design for a head light as shown and
described.

DESCRIPTION

U.S. PATENT DOCUMENTS

D268,442 S	3/1983	Darmon
4,495,550 A	1/1985	Visciano
D306,351 S	2/1990	Charet et al.
5,268,826 A	12/1993	Greene
5,385,500 A	1/1995	Schmidt
D365,646 S	12/1995	deBlois
D368,146 S	3/1996	Carbone
D369,873 S	5/1996	deBlois et al.
D370,988 S	6/1996	Santarsiero
D371,855 S	7/1996	Heun
D373,651 S	9/1996	Szymanski
D374,299 S	10/1996	Carbone
D385,371 S	10/1997	Yemini
5,707,137 A	1/1998	Hon
5,717,276 A	2/1998	Hsu
5,749,644 A	5/1998	Carbone
5,765,938 A	6/1998	Roussou et al.
5,791,763 A	8/1998	Kam-Hoi

FIG. 1 is a front/side elevational perspective view of the head light;

FIG. 2 is a rear/side elevational perspective view of the head light;

FIG. 3 is a front view of the head light;

FIG. 4 is a rear view of the head light;

FIG. 5 is a first side view of the head light;

FIG. 6 is a second side view of the head light;

FIG. 7 is a top view of the head light; and,

FIG. 8 is a bottom view of the head light.

The broken lines in the figures represent portions of the head
light that form no part of the claimed design.
